COVERED CONTAINER WITH COVER
FASTENING MEANS

Charles F. Onthank, Chestnut Hill, Mass.

Application July 8, 1939, Serial No. 283,474

3 Claims. (Cl. 215—90)

This invention relates to covered containers and means for securing the covers on the containers. A principal object of the invention is to provide an arrangement wherein the securing means are readily applied and released, effectively seat the cover in ordinary use, and yet will permit the cover to lift for venting under high internal pressures. Another object of the invention is to provide means whereby the securing means are effectively positioned on a pivot wire.

A typical and practical embodiment of the invention is shown by way of example in the accompanying drawing with reference to which I shall describe the invention.

In the drawing:

Figure 1 is a vertical sectional view of a container and cover with a pair of securing members in released position.

Figure 2 is a view similar to that of Figure 1, but showing the holding members in applied or locking position.

Figure 3 is an elevation of the combination as shown in Figure 2 as seen, for example, from the right of the latter figure.

Figure 4 is a view similar to that of Figure 3, but showing a different form of pivotal mounting for the securing member.

Figure 5 is a fragmentary view showing a modification of the mounting of Figure 4.

Figure 6 shows a securing member in perspective.

Figure 7 shows in rear elevation a somewhat modified form of securing member and a portion of a pivot wire with positioning means for the securing member.

Figure 8 shows the securing member of Figure 7 in side elevation.

Figure 9 is a section substantially on line 9—9 of Figure 7, and

Figure 10 is a partial view similar to that of Figure 7 showing a modified form of positioning means for the securing member.

Referring to the drawing, and first to Figures 1 to 3 and 6, reference numeral 10 designates generally a container, here shown as being a jar which may be of glass and of substantially cylindrical form.

The circular mouth of the container has a flat lip 11 from which the outer surface of the container is downwardly flared at 12 to a peripheral shoulder 13 under which is engaged a wire 14 whose ends are twisted together or otherwise suitably united. Upward displacement of the wire is prevented by shoulder 13 and downward displacement is opposed by the downwardly flared

portion 15 of the container, the wire being suitably tensioned.

A circular cover 16 of glass or other suitable material has a flat marginal portion 17 in overlying relation to the lip 11 and as here shown has a depending circular flange 18 which serves to center the cover on the container. A sealing gasket 19 is interposed between the lip 11 and the marginal portion 17 of the cover. Adjacent the lip the cover has substantially the same diameter as the lip, being flared upwardly, however, and into an upstanding flange 20 which has a relatively thin rounded upper edge 21 which lies substantially directly above the wire 14, or perhaps somewhat inwardly as regards the latter.

At least a pair of holding or securing members in the form of spring clips are provided and these are pivoted on the wire 14 at diametrically opposite points. Each of these clips, generally designated at 22, is, as here shown, formed from a strip of relatively heavy springy, although deformable, metal, the strip being of substantial width. The strip is bent at 23 to form substantially rectangularly related portions 24 and 25, the latter of which is given a slight bend or outward offset at 26. The terminal part of the portion 25 is centrally recessed at 27 so that a pair of spaced apart fingers 28 and 29 are provided. The ends of these fingers are bent to form the eyes 30 and 31 through which the pivot wire 14 is threaded prior to its application to the container, or the finger ends may be directly bent around the wire. Obviously, they need not be bent completely around the wire, but only to a sufficient extent to retain the parts in operative relation.

The terminal part 32 of portion 24 is bent back under the latter on a fairly round bend, as here shown, and extends to a point adjacent the portion 25. At its end the portion 32 is bent or hooked to give a shallow, transverse, channel-like formation 33. The region of portion 32 adjacent the hook 33 is bent or offset at 34 toward the part 24.

With the members 22 pivotally mounted on wire 14 and the cover 16 in place, they are swung upwardly to snap the hooked portions 33 into engagement with the relatively narrow flange edge 21, as shown in Figure 2, an intermediate position being shown in Figure 1. The relation of parts is such that the parts 32 are flexed toward the overlying portions 24, which latter are preferably somewhat downwardly and inwardly inclined as shown in Figure 2. In the applied position of Figure 2, however, the offset portions

34 are still out of contact with the overlying portions 24 so that full flexing of the parts is secured. A much stiffer lock is secured if the parts are so proportioned that the offsets 34 abut the portions 24, but this is ordinarily unnecessary.

Since there is a relatively small area of engagement between the shallow, hook-like ends 33 and the narrow rim 21, and the engagement or disengagement of these parts, in applying or releasing the clips, is accomplished with the least possible effort, and manipulation is greatly facilitated. Furthermore, very quick release is assured by the offsets 34 which are so proportioned that the clips are free of the flange edge as soon as their end portions 33 have moved from the latter. The best possible compressive effect on the gasket is secured, since there is a substantially direct downward pull on the cover due to the positioning of the edge 21 substantially directly above the pivot wire.

In venting, upon the development of high internal pressures, the cover lifts without any unlatching tendency on the clips, the portions 32 flexing toward the portions 24. Flange 18 guides the cover in the venting operation and has sufficient clearance with the container walls so that venting can take place therebetween.

I have found that with the recess 27 omitted and the end of portion 25 rolled throughout its width about the pivot wire, which is circularly bent, there is a binding effect so that when the clips are applied to the cover the wire tends to be twisted and its torsion consequently tends to disengage the clips. This tendency is practically avoided by providing the relatively narrow, spaced apart fingers which project substantially beyond the solid portions of the clips, and consequently the provision of these fingers constitute a preferred feature of construction.

It will be noted that the vertical contour of the container and cover adjacent the gasket is such that any outward bulging of the latter will not reach outside the projection of the cover or container so that there will be no interference with the clips. Such possibility of interference would also be eliminated by the bends 26, these bends contributing also to the resiliency and adaptability of the clips.

The same clip 22 is shown in Figure 4, but in this case the container 35 is formed with a pair of circumferentially spaced lugs 36 and 37 which are pierced to receive a pivot pin 38 upon which the clip is mounted as before. The fingers of the clip may be clinched on the pin to prevent longitudinal displacement of the latter or the pin may be headed or bent or otherwise secured in position. The recess 27 could, of course, be omitted.

In Figure 5 the container 39 is provided with a single lug 40 pierced to receive a pivot pin 41 and of a size to be received in the recess 27 in the manner shown, the clips straddling the lugs.

In Figures 4 and 5 I have shown the same cover as in Figures 1 to 3 and the pivoting axis in each case is substantially directly below the edge 21, as described in connection with the first embodiment.

The pivot arrangements of Figures 4 and 5, involving the lug formations, are desirable from a number of standpoints. The cost of a neck wire is largely saved and assembly can be made much more rapidly. The jar is easier to clean and damaged clips are much more readily replaced.

In Figures 7 to 9 the clip 40 is generally the

same as that shown in the other figures, but in this case it is formed with a re-inforcing rib 41 which runs centrally along the angularly related portions 42 and 43, being branched at 44 and 5 45 into the spaced-apart fingers 46 and 47 which are bent around a pivot wire 48. In this case, however, the pivot wire has an off-set 49 between the fingers 46 and 47 and consequently the clip is securely held against sliding in either direction 10 on the wire. This is a feature of considerable importance, since in original manufacture the clips are strung on the wire and later on are applied to the container. Due to the offsets, as 15 at 49, in the wire, the clips maintain their relative positions lengthwise of the wire at all times. Another advantage of the clip shown in Figures 7 to 9 is that, due to the struck-up longitudinally extending rib, lighter gauge metal can be used.

In Figure 10 the same design of clip is shown 20 as in Figures 7 to 9, but in this case the wire 50 is provided with two small downward offsets 51 and 52 between the clip fingers. With this arrangement there is greater security in case the fingers are bent or looped very loosely about the 25 wire. With the clip tensioned in use, for example, the bottoms of the loops are engaged with the bottom of the wire and the downward offsets are fully effective. Under the same conditions the loops might be able to slip past the upward offset of Figures 7 and 9. It will be understood that the form of offset of these latter figures could be directed downwardly as in Figure 10, if desired.

While I have shown a preferred configuration 30 of the bent-under portions of the clips and a preferred form of container cover for cooperation therewith, it will be understood that the invention is not intended to be limited in these respects. Variations in details of form and arrangement are possible without departure from the invention and accordingly I do not limit myself in these respects except as in the following claims.

This application is a continuation-in-part of 40 my application Serial No. 156,418, filed July 29, 1937.

I claim:

1. The combination with a container in the form of a jar, of a cover for the mouth of the 50 jar having a marginal portion adapted to overlie the jar lip, and means for yieldingly holding said cover operatively on said jar, said means comprising a plurality of spring clips each of which 55 comprises a strip of springy metal of substantial width bent transversely to form two portions at an angle to each other, a wire surrounding the container below said lip, the end of one portion of each of said clips being centrally recessed whereby to form a pair of spaced apart fingers whose ends are bent around an arcuate portion of said wire as a pivot, the recess providing a clearance for the wire between said fingers, the width of the strip being such for the purpose of strength that if its full width were rolled about the wire a binding effect would result upon pivoting but the fingers having a sufficient free length and being of such small width that binding effect upon pivoting is substantially avoided, the other portions of said clips being operatively engageable over the top of said cover.

2. The combination with a container in the form of a jar, of a cover for the mouth of the jar having a marginal portion adapted to overlie the jar lip, and means for yieldingly holding said cover operatively on said jar, said means comprising

ing a plurality of spring clips each of which comprises a strip of springy metal of substantial width bent transversely to form two portions at an angle to each other, a wire surrounding the container below said lip, the end of one portion of each of said clips being centrally recessed whereby to form a pair of spaced apart fingers whose ends are bent around an arcuate portion of said wire as a pivot, the recess providing a clearance for the wire between said fingers, the width of the strip being such for the purpose of strength that if its full width were rolled about the wire a binding effect would result upon pivoting but the fingers having a sufficient free length and being of such small width that binding effect upon pivoting is substantially avoided, said wire being offset between the fingers of each clip whereby to position the clips on the wire, the other portions of said clips being operatively engageable over the top of said cover.

3. The combination with a container in the form of a jar, of a cover for the mouth of the jar having a marginal portion adapted to overlie

the jar lip, and means for yieldingly holding said cover operatively on said jar, said means comprising a plurality of spring clips each of which comprises a strip of springy metal of substantial width bent transversely to form two portions at an angle to each other, a wire surrounding the container below said lip, the end of one portion of each of said clips being centrally recessed whereby to form a pair of spaced apart fingers whose ends are bent around an arcuate portion of said wire as a pivot, the recess providing a clearance for the wire between said fingers, the width of the strip being such for the purpose of strength that if its full width were rolled about the wire a binding effect would result upon pivoting but the fingers having a sufficient free length and being of such small width that binding effect upon pivoting is substantially avoided, said wire being offset downwardly between the fingers of each clip whereby to position the clips on the wire, the other portions of said clips being operatively engageable over the top of said cover.
